his Attorneys

UNITED STATES PATENT OFFICE

GEORGE G. PENROSE, OF CHICAGO, ILLINOIS

PACKING CARTON

Application filed November 28, 1927. Serial No. 236,072.

My invention relates to cartons or containers of the class in which articles such as beans, peas, rice or other foods may be packed for shipment, display and sale.

One of the objects of the present invention is to provide a carton or container in which the articles packed therein may be exposed to view of intending purchasers, without opening the package or breaking the seal 10 (when such packages are sealed).

Another object is to provide a carton or container of the class described, in which the transparent window light or material is covered temporarily during packing, transportation and handling to protect such window light from damage prior to being sold and delivered to the ultimate consumer.

Another object is to provide a carton or container of the class described, having a window light mounted in such a manner that it may be cemented to the carton to form an air-tight joint there-between.

With the above and other objects in view, which will more particularly appear from the following description, I have illustrated in the accompanying drawings, the preferred style of my invention, and in said drawings I have indicated the same part throughout the various views by the same reference numeral.

Figure 1 is a plan view of a flat blank cut out in the shape shown, and scored as indicated for folding into a rectangularly shaped carton.

Figure 2 is a front elevation of one of my cartons showing the top open, ready to be filled.

Figure 3 is a section view of a portion of the front wall taken along the line $\alpha-\alpha$ showing the parts forming the window light.

Figure 4 is a section view along the same line as $\alpha-\alpha$ and showing a variation from that shown in Figure 3.

Figure 5 is a detail view of the transparent window 7 enclosed in the frames 8.

In the accompanying drawings I have shown two variations of construction of my cartons. The preferred style shown in Figure 3 is adapted especially for the packing of articles where it is required that the carton shall be sealed air tight to prevent de-

terioration of the contents by air, moisture or other deleterious substances. The variation shown in Figure 4 is equally useful for all purposes, excepting that the method of construction does not lend itself to the manufacture of a carton which is always perfectly hermetically sealed and is usable wherever the contents are not injured by air or moisture entering the carton through openings where the carton is not perfectly sealed.

In the manufacture of my said cartons, the first step is to stamp or cut out a blank as 1 shown in Figure 1, from a single flat sheet of heavy card-board, straw board or the like suitable material. At the top and bottom, the blank is cut to form a plurality of flaps 11, and 13 made integrally with the blank for folding over to close the top and bottom ends respectively. At a suitable place in one of the walls of the carton as at 3 a cut is made 15 in the blank, either circular, oval, or any other desired shape, partially cutting out a piece of the card-board as 16, but leaving a narrow portion to attach the disk 16 to the blank, for the purposes hereinafter explained. The blank is also scored in the usual manner 20 along the dotted lines to indicate and facilitate folding to form the carton shown in Figure 2.

A transparent piece of material 7, of celluloid, glaice or other similar transparent material, of a size large enough to more than cover the opening formed by the cut 3, is cut out, preparatory to covering the said opening. The edges of this piece of transparent material are carefully covered with any suitable adhesive, and it is attached to the part which is to form the inside wall of the carton by pressing firmly over the opening formed by the cut 3 and against the said card-board, 35 until the cement sets firmly, as shown in section in Figure 4.

By this construction, when the disk 16 is removed, as hereinafter explained, it leaves an opening in the wall of the carton, covered by the transparent material 7, forming a window through which the contents of the carton may be viewed for inspection by any intending purchaser, without the necessity of breaking the seals, or opening the flaps at the 40

top of said carton. While this form of construction offers all the opportunity required to view and inspect the contents of said carton, as explained, yet by reason of the fact that it is difficult, in practice, to make the adhesive spread evenly over the glazed surface of the transparent materials in general use, and the further reason that if the adhesive fails to spread evenly and cover the entire circumference of the said opening it leaves one or more places where air may enter the said carton, this construction is not always reliable for articles requiring to be hermetically sealed to preserve them against deterioration. To make the carton perfectly air tight, I prefer to attach the transparent window material 7 in the manner shown in Figure 3. In this construction the transparent material 7 is cut to the required size and shape, and two frames slightly larger than 7 as 8, 8 are cut out of paper, card-board or other suitable material, each of said frames 8, 8 having a central opening to correspond to the size and shape of the opening formed at 3 in the wall of the carton. Suitable adhesive is applied to both sides of the transparent material 7 near the edge and also to one side of each of the frame members 8, 8. The three parts are then assembled, with the transparent material between the sides of the frames 8, 8, the sides having the adhesive toward the member 7, with the frame members extending without and beyond the transparent member in all directions, and the three parts are firmly pressed together, preferably in a machine adapted for the purpose, with suitable heat applied thereto, to cause the adhesive to spread thinly and evenly over all of the surfaces in contact, to provide a perfectly airtight joint when fully set. After this transparent window member has thus been formed and fully dried, adhesive is applied to the frame member 8 on one side of said member, and it is placed against the inner wall of the carton, with the opening in the transparent window member in register with the opening formed by the cut 3 in the carton, and the said window member is pressed tightly against said wall until the parts adhere fully and perfectly together, thus forming an air-tight joint therebetween. By making the window member in the separate piece as above explained, it permits me to use suitable machinery to produce uniform and perfect contact and adhesion between the parts, and provides the window member with a surface to which the adhesive generally employed will adhere more perfectly to make the best and surest joint possible.

After the window member has been cemented to the blank 1 in either of the methods above described, the blank is folded along the dotted lines, and the edges 9 and 10 are cemented together, and the bottom flaps 11 are folded over and cemented together to

form the carton with open top shown in Figure 2. After the carton is filled with the articles 12 intended to be placed therewithin, the flaps 13 at the top are folded down, and cemented together to close the said carton ready for shipment, display or sale as required. 70

In the manufacture of my said carton, I have preferred to make the cut 3 only part way around the opening, as shown, leaving the disk 16 in said opening only partially cut out so long as required to protect the transparent material 7 covering said opening from being damaged in packing, handling and shipping. The disk 16 might be cut entirely 80 out, if desired, but by leaving it in position until the merchant is ready to display or sell the goods, all likelihood of the transparent window being damaged is prevented and if preferred, lighter and less expensive material may be used, thereby reducing the cost of said carton. When it is desired to display the articles 12 enclosed within the carton, the connection 15 at the bottom of the disk 16 may be severed, and the disk raised exposing the 90 contents to view through the window opening. If desired, the disk may be left on the carton, and lowered again when through displaying, using the upper connection 14 as a hinge, or if preferred, the upper connection 95 14 may also be severed, and the disk entirely removed, exposing said window opening and the contents to view at all times.

By employing my said improved carton a manufacturer is assured that he can pack 100 his product in his factory, and make certain that it will reach the customer in the same neat, clean and palatable condition in which it has left his factory. Further, it insures that the customer may inspect the articles 105 which he is purchasing, and make sure before purchasing, that they are of the kind, size, and quality which he desires, and that they will be free from any damage from air, moisture, or insects, instead of buying "sight-unseen" as is at present the case with all packed and sealed articles. It also insures that the articles have not been opened, and exposed to dust, dirt, or handling of any kind, which is greatly to be desired and will 110 be highly appreciated by a discriminating public.

It will be apparent that the size and shape of the carton are immaterial, so long as it is constructed in the manner above described. 120 It will also be seen that merchants, or others, desiring, may purchase the cartons for putting up goods for display and for sale, as in the "cash and carry" stores, and the customer waiting upon himself, can see the kind 125 and quality of the goods offered for sale, without the merchant being required to mark each separate package to indicate the kind or quality. It will also be seen, that the factory packing a high grade quality of goods 130

will be able to show the better quality of his goods, and will have the advantage which such quality should secure in competitive sales.

5 Having thus described my invention, what I claim and desire to secure by Letters Patent, is the following:—

10 A carton having an opening in the wall thereof; and a closure for said opening, said closure consisting of two flat rings having perforations corresponding to the perforation in the carton wall and a transparent sheet interposed between said rings, the edges of said sheet being hermetically sealed between said rings and the outer of said rings being adhesively secured to the inner wall of said carton around the opening therein.

15 In testimony hereof I have signed the foregoing specification.
